CLAIM

The ornamental design for wound therapy packaging with surface ornamentation, as shown and described.

DESCRIPTION

The FIGURE is a wound therapy packaging with surface ornamentation, showing my new design.

The broken line arrows and hands and broken line numbering located within the solid line rectangles of the figure form no part of the claimed design. All other broken lines in the figure illustrate the portions of the wound therapy packaging with surface ornamentation that form no part of the claimed design.

All sides not shown in the view form no part of the claimed design.
